UNITED STATES PATENT OFFICE.

JOHN J. TATUM, OF BALTIMORE, MARYLAND.

STAKE-HOLDER FOR FLAT-CARS.

1,277,775.

Specification of Letters Patent.

Patented Sept. 3, 1918.

Application filed November 7, 1916. Serial No. 130,028.

To all whom it may concern:

Be it known that I, JOHN J. TATUM, a citizen of the United States, residing at Baltimore, State of Maryland, have invented certain new and useful Improvements in Stake-Holders for Flat-Cars, of which the following is a specification.

In practice, it has been found that with stake holders of the type now commonly employed, the stakes work loose and sometimes entirely out of the stake holder under the vibrations of the cars. This is particularly likely to occur when temporary stakes are driven into the pockets to support lumber and like materials that are being loaded upon the cars because these temporary stakes are more or less roughly fashioned, do not fit the stake holders accurately and in many instances do not project into the stake holders to the full depth of the latter. It is a matter of the highest importance to provide stake holders that will with certainty hold the stake against accidental dislodgment therefrom because it has sometimes happened that stakes have become dislodged from cars loaded with lumber and pieces of the lumber have, under the vibration and sway of the cars worked out to such a position as to side-swipe a train on another track and serious wrecks have resulted therefrom.

It is, therefore, the primary object of the present invention to provide a stake holder which will effectually hold a stake securely therein no matter how roughly the latter may be fashioned.

A further object of the invention is to provide a stake holder which will effectually serve the foregoing purpose but which will be of simple construction and economical to manufacture.

Further objects and advantages of the invention will be set forth in the detailed description which now follows:

45 In the accompanying drawing—

Figure 1 is a front elevation of one form of my improved stake holder.

Fig. 2 is a vertical sectional view therethrough.

50 Fig. 3 is a plan view of a modified form of stake holder.

Fig. 4 is a vertical sectional view of the stake holder illustrated in Fig. 3.

Fig. 5 is a front elevation of a form of

stake holder embodying a further modification of the invention. 55

Fig. 6 is a vertical section of the stake holder illustrated in Fig. 5, and

Fig. 7 is a vertical, sectional view of a stake holder embodying a further modification of the invention. 60

Like numerals designate corresponding parts in all of the figures of the drawing.

In the form of the invention illustrated in Figs. 1 and 2, the stake holder is embodied in an integral structure comprising securing flanges 10 and the central off-set body portion 11, the side walls 12 of the latter being continued below the front wall 13 thereof. The inner faces of the side walls 12 and the 70 inner faces of the front wall 13 are provided with horizontal under-cut ribs 14, having the inclined faces 15 and the substantially horizontal, under-cut faces 16. This construction permits the ready introduction of a stake into the holder but effectually resists withdrawal of the stake and prevents the stake from working out of the holder under the vibration of the car. 75

It is not essential that the front wall 13 be terminated short of the bottom of the side walls 12 but I find such an arrangement of parts of advantage since, if it becomes necessary to remove the stake from the holder, the fact that the stake projects 80 somewhat below the front wall 13 renders it possible to drive upwardly upon the lower end of the stake. However, it is to be understood that the invention contemplates making the front wall 13 as deep as 85 the side walls 12.

In the form of the invention illustrated in Figs. 3 and 4, the stake holder embodies securing flanges 20 and a central U-shaped body portion 21 constituting a receiving 95 pocket for the stake. Both the front wall 22 of the body portion and the side walls 23 thereof are studded with barb like projections disposed in staggered relation and comprising the curved and inclined faces 24 and flat, horizontal, under faces 25. These barb like projections may be formed by striking them from the material of the front and side walls as clearly illustrated in Fig. 4. It is apparent that the shape of the barb 100 like projections illustrated in Figs. 3 and 4 is such as to permit downward movement of the stake holder but to resist upward move- 105

ment of the stake with relation to the stake holder.

In the form of the invention illustrated in Fig. 5, the stake holder comprises the securing flanges 30 and the off-set body 31 corresponding in a general way to the structure illustrated in Figs. 1 and 3. In this modified form of the invention, however, semi-spherical bosses 32 are struck, or otherwise formed upon, the front and side walls 33 and 34, respectively of the body portion. These bosses serve to bite into a stake and to aid in preventing the dislodgment of the stake from the stake-holder.

15 In the modified form of the invention illustrated in Fig. 7, the stake holder is, in its general form, substantially like the stake holder shown in Figs. 1 and 2, except that continuous horizontal ribs are not employed 20 but in lieu thereof the front wall 13^a and the side walls 12^a of the stake holder are studded with rows of separated barb like projections having inclined front faces 40 and undercut lower faces 41.

25 It is apparent that in the various modifications of the invention, the several types of holding devices employed are disposed in such manner that they will engage a stake even though the latter be so roughly fashioned that it will project all the way through 30 the body portion of the stake holder. This is due to the fact that both the front and side faces of the stake holder are provided with holding means, these holding means being disposed at a plurality of points in the 35 height of the body portion of the stake holder.

It is also obvious that the projections in the form of ribs, barbs or lugs could be 40 formed on plates attached to the inner faces of the stake pocket.

Having described my invention what I claim is:

1. A stake pocket having stake engaging projections transversely located across the 45 inner walls of the pocket, so as to form opposing shoulders against the removal of the stake.

2. A stake pocket having walls to encompass a stake and provided with projecting 50 lugs transversely located across the inner walls of the pocket, forming opposing shoulders to resist the removal of the stake.

3. A stake pocket having walls to encompass a stake, and provided with projecting 55 portions transversely located across the inner walls of the pocket, forming opposing shoulders to resist the removal of the stake.

4. A stake pocket in combination with a wooden stake having walls with projecting 60 lugs or ribs, transversely located across the inner walls of the pocket, the bottom of the lugs or ribs tapering outwardly from the walls one toward another on opposing walls and forming projecting shoulders at the ends 65 of the lugs to resist the movement of the stake in one direction.

5. A stake pocket having a plurality of walls with a plurality of lugs or ribs formed 70 on the inner walls and projecting one toward the other to form opposing shoulders on the lower edges of the lugs or ribs, such lugs or ribs being located throughout the face of the inner walls of the stake pocket so as to form 75 opposing shoulders, preventing the removal of the stake forced therein irrespective of whether the stake be forced part the way or all the way through the depth of the pocket.

The foregoing specification signed at Baltimore, Maryland, this 17th day of October, 1916.

JOHN J. TATUM.
